UNITED STATES PATENT OFFICE.

1. **FRED S. HOVER, OF HYDE PARK, NEW YORK.**
Improvement in the construction of detectors for wireless telegraphy and telephony.

1,318,277.

Specification of Letters Patent. Patented Oct. 7, 1919.
Application filed December 14, 1917, Serial No. 207,140. Renewed February 28, 1919, Serial No. 279,887.

To all whom it may concern:

Be it known that I, **FRED S. HOVER**, a citizen of the United States, residing at Hyde Park, in the county of Dutchess and State of New York, have invented new and useful Improvements in Detectors for Wireless Telegraphy and Telephony, of which the following is a specification.

This invention relates to a detector for wireless telegraphy and telephony, and the object is to provide for rendering accessible every part of the mineral customarily employed in such apparatus, means being provided for adjusting the detector element of silver wire or the like, permitting the movement thereof to any part of the surface of the mineral.

A further object is to provide means for inclosing the detector members, so that the latter will be free from dust and changing atmospheric conditions.

With the foregoing and other objects in view, the invention consists in the novel construction, combination and arrangement of elements hereinafter described and claimed.

In the drawings:

Figure 1 is a longitudinal section of the device.

Fig. 2 is a transverse section on line 2—2 of Fig. 1.

A base portion of insulating material is designated 10 and mounted thereon are brackets 11 and 12 of any suitable metal, the binding posts being designated 13 and 14. A tubular member of glass is shown at 15, and means are provided for entirely inclosing and sealing the detector members within this glass cylinder. One end of the cylinder is closed by a body portion 16 of insulating material, this member being provided with a bore 17 through which the pin or bolt 18 extends, the latter having an outer threaded end engaged by a nut 19. A head 20 has soldered thereto a spring 21 which is in positive contact with mineral 22, mounted within a larger bore 23 formed within the body portion of insulation and communicating with the bore first named. Mineral 22 is secured by any suitable substance shown at 24.

The opposite end of the glass tube is closed by means of a body of insulation shown at 30 inclosing a metallic cylinder 31 receiving a metallic flanged head 44 having a bearing in bracket 12, said cylinder 31 carrying rigidly a flanged member 31' constituting a

knurled head by means of which said member 31 may be rotated. Cylinder 31 is in electrical communication with bracket 12 and binding screw 14 through metallic head 44. A bore 32 provides for the screw 33 having threaded connection with said bore, the outer portion of the screw being encircled by a coiled spring 34, and having a knob 35 provided with a knurled edge affording means for rotating the screw for moving the plunger 36 longitudinally and thereby adjusting the position of rod 38 carrying the silver wire detector element 40.

Screw 33 is retained by a nut 41, and a collar 42 bears against the opposite end of the plunger. The rod 38 passes through apertures in the head 44, in the plunger 36, and in the head 45, these apertures being in alignment and eccentric with reference to the screw 33.

Rod 38 carries at one end thereof a knurled knob 47, and the rod is encircled by a spring 48 bearing against the head 45 and bearing against a collar 49 engaging the surface of the plunger 36. The end of the rod 38 is provided with an aperture extending transversely therethrough, for the purpose of mounting the element 40, and a screw 50 retaining said element in position.

In view of the construction described any point on the surface of the mineral may be engaged by the end of the detector element 40, the latter being mounted on a rod 38 as specified providing for movement in a curved path with reference to the main axis of the rotatable member.

What is claimed is:

1. In a device of the class described, a tubular member of insulating material, means for closing one end thereof and for mounting a mineral, and means for mounting a complementary detector member and comprising a device rotatable within the tubular member, and a rod eccentrically mounted within the rotatable device and supporting said detector member last named.

2. In a device of the class described, a tubular member of insulating material, means for closing one end thereof and for mounting a mineral, means for connecting said mineral with a binding post or the like, means for mounting a complementary detector member and comprising a rotatable element mounted within the opposite end of the tubular member, said rotatable member being provided with a bore, a plunger

operable within said bore, means for operating the plunger, a rod extending through the plunger and located eccentrically with reference to the main axis of the plunger, said rod carrying the complementary detector member.

3. In a device of the class described, a tubular member of insulating material, means for mounting a mineral element therein, a complementary detector element, a bushing of insulating material mounted within one end of the tubular member, a rotatable tubular member mounted within the bushing, means for operating said rotatable member, a plunger operating within a bore in said rotatable member, a screw for controlling the position of the plunger, said plunger being provided with an eccentrically located bore, a rod extending through said bore, and means carried by the rod for

supporting the complementary detector member.

4. In a device of the class described, a tubular member of insulating material, means for mounting a mineral therein, a bushing carried by one end of the tubular member and provided with a bore, a rotatable tubular member mounted within said bushing, a plunger within the rotatable member, a screw for operating the plunger, a rod passing through said plunger and located eccentrically with reference to the axis thereof, a detector element carried by said rod, and coöperating with the mineral, a spring for controlling the position of the rod, said rod being manually adjustable against the tension of the spring.

In testimony whereof I affix my signature.

FRED S. HOVER.
